UNITED STATES PATENT OFFICE.

ALDA F. HAWKINS, OF FORT WORTH, TEXAS.

BATTERY-TERMINAL-FASTENING DEVICE.

1,355,396.

Specification of Letters Patent.

Patented Oct. 12, 1920.

Application filed June 2, 1920. Serial No. 385,944.

To all whom it may concern:

Be it known that I, ALDA F. HAWKINS, a citizen of the United States, residing at Fort Worth, in the county of Tarrant and State of Texas, have invented certain new and useful Improvements in Battery-Terminal-Fastening Devices, of which the following is a specification.

This invention relates to new and useful improvements in battery terminal fastening devices.

The invention has particularly to do with certain improvements over the construction known in my co-pending application, filed April 5th, 1920, S. N. 371,458. The particular improvements have to do with provisions whereby the same type of resilient fastenings which is used to secure the post or terminal in the cap may also be used as a packing between the cap and the terminal plate which as will be obvious makes more economy and uniformity in manufacture as well as replacement. A further improvement which is involved is that of more adequately cleaning the fastening element and the packing member.

In carrying out the invention a terminal post is provided with an annular shoulder or other radial projection and the upper edge of the opening in the cap surrounding the post is provided with an annular seat below the flange of the post. The post is preferably provided with a circumferential groove contiguous to the annular seat. A resilient or elastic ring or the like is flush below the flange and received in the groove, whereby it also engages in the seat. The lower edge of the opening in the cap is beveled or otherwise formed to provide an annular seat for a resilient or elastic ring which surrounds the base of the post and rests on the terminal plate. It will be seen that the same type of ring may be used at the base of the post which is used in the groove thereof, and also that the battery terminal is yieldably supported whereby it is given some play with relation to the cap and at the same time a tight joint is had so that no liquid can pass between the post and the cap.

The invention will be more readily understood from a reading of the following specification and by reference to the accompanying drawings, in which an example of the invention is shown, and wherein:

Figure 1 is a side elevation of a portion

of a storage battery cell showing the cap fastened on the terminal post in accordance with this invention.

Fig. 2 is a plan view of the same, 60
Fig. 3 is a longitudinal sectional view, and

Fig. 4 is a plan view of one of the rings. In the drawings the numeral 10 designates a hard rubber cap of the cell of an ordinary storage battery which is constructed in the usual manner. The cap has a vertical opening 11 for receiving the terminal post 12 of the usual terminal plate 13, which latter is secured to the battery 70 plate 14 in the usual manner. The cap 10 has an annular seat 15 in its under side surrounding the opening 11 and beveled inwardly as is best shown in Fig. 3. An elastic ring 16 is slipped down around the post 75 12 so as to rest on the plate 13 and to be received in the seat 15. This ring or gasket prevents the solution from passing out through the opening 11 as will be obvious, of course, provided that the parts are in 80 close contact.

The terminal post 12 is provided with a circumferential groove or recess 17 and an annular shoulder or flange 18 which overhangs the groove and is positioned slightly 85 above the top of the cap 10. The remainder of the post above the flange is finished in the usual way. An annular seat 19 surrounds the upper end of the opening 11 in the top of the cap and is beveled inwardly. 90 In order to fasten the cap in position an elastic or resilient ring 20 is forced down over the flange 18 so as to ride into the recess 17 and the seat 19. The groove 17 being concave, the tendency of the ring is 95 to work under the flange and thus more firmly engage in the seat 19, whereby the cap 10 will be forced downward and the ring 16 caused to ride into the seat 15 as will be obvious. The ample bevel given to 100 the seat 15 permits the ring 16 to wedge firmly into the same thus providing a very effective packing and at the same time gives a yieldable connection as will be obvious.

As before stated it is preferable to make 105 the rings of rubber and particularly of a grade which will have a high degree of acid resistance; but it is obvious that the rings do not necessarily have to be made of rubber and it is obvious that a split metallic 110 ring might be used in place of the ring 20. It will be observed that the groove snugly

receives the ring 20. It is further pointed out that the ring will have such an ample bearing in the groove and also in the seat 19 as to render accidental displacement substantially impossible. In fact the ring will seat with such tenacity that a tool will be required to remove said ring 20 before the cap can be disengaged from the terminal post. It will be seen that when it is desired 10 to remove the cap it is merely necessary to pry the ring loose and remove it from the post 12. If the ring 20 is injured in removing it may be easily replaced by a new one. It is believed that the invention which has 15 been described will to a large extent eliminate broken cell caps and will certainly make for cheaper repairs.

It is pointed out that both rings may be made of rubber or similar elastic material 20 and when so made are interchangeable. This makes for economy and quick assembly. However it is not my intention to limit the invention to the use of a rubber ring and this has particularly to do with the fastening ring 20.

What I claim, is:

1. In a battery terminal fastening, the combination with a cell cap having an opening formed therethrough, said cell cap being 30 provided upon its lower side with a tapered seat increasing in diameter downwardly, a terminal post extending through said opening and provided near the upper surface of the cap with an annular groove which is 35 curved in cross section, a stop element carried by the lower end of the terminal post and projecting laterally beyond the same and adapted to be arranged beneath the cell cap in proximity to the tapered seat, a 40 highly elastic and circumferentially expandable and contractible ring carried by the lower end of the terminal post and arranged between the stop element and the tapered seat, and a second highly elastic and circumferentially 45 contractible and expandable ring adapted for insertion within said groove and to contact with the upper portion of said cap, the last named ring tending to move 50 downwardly with relation to the cap when contracting within the annular groove.

2. In a battery terminal fastening, the combination with a cell cap having an opening formed therethrough, said cell cap being provided upon its upper face with a tapered seat decreasing in diameter downwardly and 55 surrounding said opening, said cell cap being provided upon its lower side with a tapered seat increasing in diameter downwardly and surrounding said opening, a terminal post extending through said opening 60 and provided near the upper surface of the cap with an annular groove increasing in depth inwardly and having an outwardly extending flange above the groove, a stop element carried by the lower end of the terminal post and projecting laterally beyond the same and adapted to be arranged beneath the cell cap in proximity to the lower tapered seat, a highly resilient and circumferentially expandable and contractible ring 65 carried by the lower end of the terminal post and arranged between the stop element and lower tapered seat, and a second highly resilient and circumferentially contractible and expandable ring arranged within said 70 groove between the flange and upper seat, the last named ring tending to move downwardly with relation to the cap when contracting within said groove.

3. In a battery terminal fastening, the combination with a cell cap having an opening formed therethrough, of a terminal post extending through said opening and provided near the upper surface of the cap with an annular groove increasing in depth 85 inwardly, a resilient and circumferentially expandable and contractible ring inserted within the annular groove and engaging the upper portion of the cap, said ring tending to move downwardly with relation to the 90 cap when contracting in its groove, a stop element secured to the lower end of the terminal post, and a resilient circumferentially expandable and contractible ring surrounding the lower end of the post and 95 confined between the stop element and lower portion of the cap.

In testimony whereof I affix my signature.

ALDA F. HAWKINS.
